UNITED STATES PATENT OFFICE.

JULIUS O. EIS AND EDWARD J. KNAUFF, OF CHICAGO, ILLINOIS.

ELECTRIC FITTING.

1,301,546.

Specification of Letters Patent. Patented Apr. 22, 1919.

Application filed August 29, 1917. Serial No. 168,713.

To all whom it may concern:

Be it known that we JULIUS O. EIS and EDWARD J. KNAUFF, both citizens of the United States, residing at Chicago, in the 5 county of Cook and State of Illinois, have invented certain new and useful Improvements in Electric Fittings; and we do hereby declare the following to be a full, clear, and exact description of the invention, such 10 as will enable others skilled in the art to which it appertains to make and use the same.

In its general aspects, our joint invention relates to electric fittings and aims to provide simple, convenient and cheap means 15 for affording electrical connections between portions of electric fittings in one of which the circuit is grounded to a shell or casing. More particularly, our invention relates to a 20 connecting plug or coupling member for use with a socket having circuit terminals formed respectively by a metal shell and by a contact member insulated from this shell, and having its shell equipped with means 25 for interlocking with a portion of the plug or coupling member. For example, in locating automobile troubles or lighting the interior of the radiator casing for any other purpose, it has become customary to use an 30 incandescent lamp connected by flexible cables to a plug inserted instead of the lamp in one of the lamp-sockets on the automobile. These sockets, according to the prevailing economical practice, are commonly 35 installed on a single-wire grounded circuit; that is to say, a circuit in which one terminal of the battery or generator is grounded through the metal chassis to the casings of the sockets, and in which the other terminal 40 is connected by insulated wires to spring-pressed contact plungers mounted in the respective socket casings and each insulated from the casing which houses the same. In making a detachable wire-terminal plug for 45 making the desired electrical connection to such a socket, it is easy to provide the connection for the contact plunger, but more difficult to provide that for the wire which is to be electrically grounded to the casing. 50 For the latter purpose, it has been customary to equip the plug itself with a metal shell or collar, and to solder one of the wires

to the collar. With this construction the cost of the shell has meant quite an item of expense, and the difficulty of securing a good 55 soldered connection has frequently led to trouble, particularly where the plugs were sold by themselves and connected to the wires by inexperienced persons. Our invention aims to overcome both of these objections by providing a construction which requires no collar and hence is less expensive, and by providing wire terminals in which each wire may readily be clamped by screws. Speaking more generally, our invention also 60 aims to provide a simple and inexpensive connector portion for detachably connecting two relatively insulated conductors to a grounded socket shell and a conductor housed by the shell, for utilizing the interlocking pin as part of the electrical connection, for securing the metal parts to the insulator with a minimum of fastening elements, for guarding against a short-circuit within the plug, and for effectively concealing 65 the interior construction so as to afford a handsome and compact appearance. Still other objects will appear from the following specification and from the accompanying 70 drawings, in which—

Figure 1 is a perspective view of a wire-terminal plug embodying our invention.

Fig. 2 is an enlarged central and longitudinal section through the same, taken vertically through Fig. 1.

Fig. 3 is a transverse section through Fig. 2, taken along the line 3—3 and looking upward.

Fig. 4 is a longitudinal section through a plug portion showing an alternative method 90 of securing certain of the metal conducting elements to each other.

Fig. 5 is an end view of the plug with all metal parts except the anchoring pin removed.

In the embodiment of Figs. 1, 2 and 3, the detachable connector member includes an insulator 1 of hard rubber or the like, in the form of a cylinder threaded near one end to receive an ornamental hollow cap 2. The 100 insulator 1 has two cylindrical bores extending longitudinally through the same and united at the lower end (when viewed as in Fig. 2) by a recess central of the end of the

insulator, thus affording an approximately oval recess at this end as shown in Fig. 5. Extending transversely through the insulator at right angles to a plane through the 5 axes of the two tubular bores and through the said enlarged recess is a metal pin 3, which is anchored in the rubber of the insulator. This pin extends at both ends beyond the insulator, so as to afford projections 10 disposed for interlocking with bayonet slots on a socket shell 4 after the manner familiar to users of automobile lamp sockets. Within one of the longitudinal bores in the insulator we mount a wire terminal 5 and 15 solder this terminal to the pin 3, the latter preferably having its central portion knurled to afford a good hold for the solder. Likewise, we mount a somewhat longer wire terminal 6 in the other cylindrical bore portion, and thereafter secure this terminal 6 to a contact plate 7 extending beyond the axis 20 of the insulator 1. For the latter purpose, we desirably equip the terminal 6 with a reduced end adapted to enter a perforation 25 in the contact plate 7 and affording an adjacent shoulder against which this plate may abut as shown in Fig. 2. Then the reduced end of the said terminal can be riveted over and may also be soldered to the contact plate, 30 though we preferably punch the latter of a contour snugly fitting the said enlarged recess portion of the insulator bore, so that the walls of this recess will prevent any lateral movement of the contact plate.

35 Each of the wire terminals 5 and 6 is desirably held in the insulator merely by a screw extending transversely through an adjacent portion of the insulator, this being the screw which also fastens the wire or 40 cable in the same terminal (such as the screws 8 and 9 of Fig. 5), so that these screws effectively hold all of the metal conducting parts (except the anchoring pin) in position. To prevent a possible short-circuiting within the plug through any looseness of fit, or bending of the metal parts, or lumping of the solder, we also preferably 45 undercut the longer terminal 6 just beyond the said shoulder so as to give this terminal a reduced shank 10 having an enlarged ring 11 spaced from its lower end. The resulting contraction in diameter affords added clearance between the cross-pin 3 and the portion of the terminal 6 adjacent thereto, and 50 the inner face of the annular enlargement 11 also affords a shoulder for a sheet of insulating material 12 which we preferably slip into the position shown in Fig. 2 before inserting the contact plate 7.

55 It will be obvious from the above that the anchoring pin 3 will form the electrical connection from the shell 4 to the shorter wire terminal 5, thus avoiding the expense of the extra metal collar heretofore used for

this purpose. Likewise, the contact plate 7 65 affords the required connection to the plunger 13 of the socket, and the spring 14 pressing against this plunger after the manner customary in sockets of the class shown not only insures good contact at the tip of this 70 plunger but also holds the pin 3 firmly interlocked with the customary bayonet slot formation of the socket shell. Moreover, by removing the cap 2, access is readily had to the screws 8 and 9, so that the wires may be 75 connected to the two terminals by any one able to use a screwdriver. Hence our device affords not only a cheap construction, but also one requiring no skill for using the same.

80 However, while we have pictured and described our invention in a particular embodiment including a contact plate riveted to one of the terminals, and arranged for clamping the wires by screws, we do not 85 wish to be limited to these or other details of the construction and arrangement here disclosed, it being obvious that the same might be modified in many respects without departing from the spirit of our invention. 90 For example, the contact plate might be bent as shown at 7^a in Fig. 4, and soldered into a slot in the wire terminal 6, in which case the latter could be even shorter than the terminal 5.

95 We claim as our invention:

1. In an attachment plug for a socket, an insulator having a pair of bores extending from one of its ends to a larger bore at its other end, a pair of wire terminals mounted 100 respectively in the first named bores, a contact plate housed by the larger bore and prevented from lateral movement by the walls of said larger bore, said plate being secured to one of the wire terminals and 105 insulated from the second wire terminal, a member carried by the insulator and disposed for affording an electrical socket connection to said second wire terminal, and means independent of said insulator for insulating the contact plate from the first wire terminal and from the said member.

110 2. In a wire-terminal plug for a socket having as circuit terminals a casing and plunger axially disposed therein, an insulator equipped with a bore substantially U-shaped in section longitudinally of the insulator, a pair of wire terminals respectively mounted in the U shanks of the said bore, a contact plate secured to one of the wire terminals and disposed in the transverse portion of the said bore and restrained from lateral movement by the walls of the said bore portion, said plate affording electrical connection with the plunger of the 115 socket, a pin extending transversely of the insulator and electrically connecting the other wire terminal with the casing of the 120 125

socket, and an auxiliary insulator disposed for insulating the said pin and the last named wire terminal from the contact plate.

3. A wire-terminal plug as per claim 2, in which the wire terminal to which the contact plate is secured has a lateral recess spac-

ing this terminal from the said pin and housing a portion of the auxiliary insulator.

Signed at Chicago, Illinois, August 25th, 1917.

JULIUS O. EIS.

EDWARD J. KNAUFF.
